[57] CLAIM

The ornamental design for a sling shot safari game, as shown and described.

DESCRIPTION

FIG. 1 is a front plan view of the sling shot safari game of the present invention;

FIG. 2 is a back plan view of the sling shot safari game of FIG. 1;

FIG. 3 is a left side plan view of the sling shot safari game of FIG. 1;

FIG. 4 is a right side plan view of the sling shot safari game of FIG. 1;

FIG. 5 is a top plan view of the sling shot safari game of FIG. 1; and,

FIG. 6 is a bottom plan view of the sling shot safari game of FIG. 1.

The broken line showing of animal figures and circular object is for illustrative purpose only and forms no part of the claimed design.
